UNITED STATES PATENT OFFICE.

JULIUS EDWARD HEILNER, OF NEW YORK, N. Y.

CORSET.

1,077,932.

Specification of Letters Patent.

Patented Nov. 4, 1913.

Application filed May 13, 1912. Serial No. 696,963.

To all whom it may concern:

Be it known that I, JULIUS EDWARD HEILNER, a citizen of the United States, residing at New York, in the county of New York and State of New York, have invented certain new and useful Improvements in Corsets; and I do declare the following to be a full, clear, and exact description of the invention, such as will enable others skilled in the art to which it appertains to make and use the same.

This invention relates to improvements in abdominal reducing corsets.

The object of the invention is to provide a corset of this class which will reduce and support the abdomen, giving a straight front to the body, and graceful and symmetrical lines to the hips by drawing the abdomen backward and upward without forcing it down.

With this and other objects in view, the invention consists of certain novel features of construction, and the combination and arrangement of parts as will be more fully described and claimed.

In the accompanying drawings: Figure 1 is a front elevation of a corset constructed in accordance with this invention; Fig. 2 is a rear elevation of the lower front portion of the corset; Fig. 3 is a detail sectional view taken on the line 3—3 of Fig. 1.

In the embodiment illustrated, a corset A of the usual long, straight front style now in vogue is shown, each half or side member B of which has an elastic fabric gore 1 inserted at a point spaced from the inner edge of the front steel about an inch, more or less, and which is here shown rectangular in form. The side members are connected at the front 40 of the corset by the ordinary fasteners F down to a point opposite the upper end of said gores 1, where the fasteners F terminate and a single hook H is employed; and below this the side members B are provided 45 with eyelets I in their contiguous edges as best seen in Fig. 2.

This corset is equipped with a belt composed of fabric flaps 2 which are secured at their rear ends to the corset at points just 50 above the upper ends of the elastic gores 1, and preferably in alinement with the rear edges of said gores. These flaps overlie the outer face of the corset and span the spaces between their points of connection and the 55 front edges of the side members B of the corset, being slightly longer than the dis-

tance between these points. These flaps have their upper edges inclined downwardly and forwardly slightly curved, and their front ends are stitched at 3 to the front edges of 60 the corset halves or members B. The lower ends or edges of these flaps preferably extend below the lower edges of the corset, and hose supporters 8 are attached thereto. Where said front ends overlie the lower ends 65 of the side members B, the former are provided with eyelets 4 registering with those lettered I, and a lacing cord 5 connects the eyelets at one side with those on the other and may be knotted in front as shown. At 70 attention is directed to the fact that the flaps 2 project obliquely downward from their outer ends where they are stitched to the side members B to their inner ends where they are laced thereto and where the inner end 75 of one flap is laced to the inner end of the other, thus forming a substantially V-shaped attachment curved downwardly along its upper edge as shown and having its lower edge constructed as yet to be described. The 80 two members of this attachment are firmly but adjustably laced to each other at a point below the fasteners F, and even below the hook H. As seen in Fig. 3, these members are longer than the side members B over 85 which they lie, when measured on the line 3—3 of Fig. 1; but the tension of the stocking supporters yet to be described will hold the inner ends of such members down, whereas there is no such tendency of the 90 body members B to be held down and on the contrary the elastic gores 1 will permit the latter to expand as the corset is laced at the rear. It follows that it is quite possible for a corpulent person to fill out the body members B, and hence the provision of the flaps 2 and their specific construction. The lower edges of these flaps have inverted V-shaped recesses 6 therein intermediate of their ends, formed by cutting out portions of the fabric, and their rear edges are also cut away for about one-half of the width of the flaps, to form tabs 7 to which hose supporters 8 are secured. Other hose supporters 8' are attached to the lower inner ends of the flaps, 100 as shown, and possibly yet others 8'' are attached to the side members B of the corset.

When the flaps 2 are connected by the cord or lacing 5 they form a belt V-shaped at its upper edge and inverted W-shaped at its 110 lower edge, and which being secured as above described, when the corset is applied

to a wearer, exerts an inward and upward pressure on the abdomen, forcing it back and holding it in this position without any downward bearing on the abdomen, which is 5 the pressure usually exerted in abdominal reducing corsets. The backward forcing of the abdomen is caused by the peculiar cut of the belt formed by the flaps and by the arrangement of the lacing cord and eyelets 10 at the lower front end of the corset.

In applying the corset the cord 5 is first inserted loosely in the eyelets 4, and after the hooks and studs F on the steel are fastened and the corset lacing at the back 15 drawn properly to cause the corset to fit the figure, this front lacing 5 is tightened to draw the opposite edges of the lower portion of the front members B toward each other to comfortably fit the wearer, and the lacing 20 may then be tied in the usual manner.

It is to be understood that in applying the corset after the hooks and studs have been fastened the abdomen is raised to adapt the belt to support it and force it backward into 25 its proper position, and then the lacing cord 5 is tightened to retain the abdomen in its raised position and to exert an inward or backward pressure thereon. This peculiarly constructed belt, while forming a support 30 and pressure exerter is very comfortable to

the user. The elastic gores 1 permit the corset to yield at its lower edge and render it more comfortable.

I claim as my invention:

In a corset, the combination with the body members whose front meeting edges have fasteners at their upper portion and eyelets at their lower portion, and elastic gores inserted in the lower edges of said body members; of a V-shaped abdominal reducing attachment comprising two flaps whose outer ends are stitched to the members above said gores and whose inner ends are provided with eyelets registering with those in said body members, each flap being slightly 40 longer than the corresponding corset member between the points where they are stitched and the registering eyelets, said flaps depending below said members and carrying hose supporters, and a lacing connecting the eyelets of the flaps and adapted to simultaneously connect the eyelets of said body members.

In testimony whereof I have hereunto set my hand in presence of two subscribing witnesses.

JULIUS EDWARD HEILNER.
